PAIR OF SPECTACLES

Harry Weissman, Great Neck, N.Y. (½ Paramount
Optical Mfg. Corp., 60-06 39th Ave., Woodside,
N.Y. 11377)

Filed Apr. 12, 1967, Ser. No. 6,663

Term of patent 14 years

(Cl. D57—1)

FIG. 1 is a top plan view of a pair of spectacles showing my new design.

FIG. 2 is a front elevational view thereof.

FIG. 3 is a side elevational view thereof.

The side not shown has substantially the same appearance as the side shown.

The dominant features of my design reside in the portions shown in full lines.

I claim:

The ornamental design for a pair of spectacles, substantially as shown and described.
